ORE CONCENTRATING DEVICE

Merle M. Newton, Colorado Springs, Colo.

Application April 18, 1932, Serial No. 605,848

2 Claims. (Cl. 74—26)

This invention relates to improvements in concentrating devices of the type employed for the purpose of concentrating ores so as to separate the gangue from the metallic values, but which can also be employed for other uses.

It is an object of this invention to produce a concentrating device of such design that it can be constructed of any size desired and which can therefore be made so small that it can be readily transported on a pack horse if necessary.

Another object of this invention is to produce a table whose surface shall be so constructed that it will have several flat panning surfaces separated by parallel riffles and whose manner of operation shall resemble that of the ordinary panning operation employed by early placer miners.

It is a further object of this invention to produce a device that can be operated by an electric motor or by a small internal combustion engine, and which can also be operated by hand, if necessary.

It is a still further object of this invention to produce a concentrating table which shall be so mounted that it can reciprocate in the direction of the riffles and in which the reciprocating means is so constructed that the amplitude of vibration of the table will exceed the eccentricity of the cam or eccentric by means of which the vibrations are effected.

The above and other objects which may become apparent as the description proceeds are attained by means of a construction and an arrangement of parts that will now be described in detail, reference for this purpose being had to the accompanying drawings in which the preferred embodiment of the invention has been illustrated, and in which:

Fig. 1 is a top plan view of the machine;
Fig. 2 is a side elevation of the machine, parts thereof being broken away;

Fig. 3 is a top plan view of the frame;

Fig. 4 is a section taken on line 4—4, Fig. 1, and shows the construction of the table, only a portion of the frame being shown;

Fig. 5 is a section taken on line 5—5, Fig. 1, and shows the box in which the concentrates are received;

Fig. 6 is a side elevation of the cam, taken along line 6—6, Fig. 7; and

Fig. 7 is a section taken on line 7—7, Fig. 6.

The machine which forms the subject of this invention is formed from two principal parts, namely, a supporting frame which has been shown in plan view in Fig. 3 and a table of which a

top plan view is shown in Fig. 1. The supporting frame is provided with side members 1 and 2, which are connected by means of diagonal frame members 3 and 4, and by brace members 5, 6, 7 and 8.

This frame has secured to its under side a plurality of blocks 9 which rest upon the supporting surface 10. Secured to the upper side of the frame are blocks 11, 12 and 13. Supports 14 are secured to the outside of the frame by means of bolts 15, which extend through elongated openings 16 in the supports and which hold the latter in adjusted position. Secured to the inner surface of each of these supports is a bracket having a projecting portion 17 which has a threaded opening for the reception of the set screw 18. The lower end of this screw rests on a plate 19 carried by the upper surface of block 9 and the screw is employed for adjusting the position of the supports in leveling the table.

Secured to opposite sides of the supports 14 are plates 20 and 21 in which the rollers 22 are journaled. These rollers serve to support the table which will now be described. The table consists of a frame having side members 23 and 24 and end members 25. A central member 26 is located half way between members 23 and 24 and the space between member 26 and the outside frame members is filled by planks 27. The table is provided along one side with an upwardly extending wall 28 and upwardly extending end walls 29 and 30. The table is slightly longer than it is wide and the ends are inclined with respect to the sides so that the table has the general appearance of a diamond or a rhomb.

Secured to the under side of the side members 23 and 24 are channels 31 which rest on the rollers 22 and form tracks in which the rollers move. The side 28 is connected with side 29 by means of a short piece 32 which is inserted at this point for the purpose of providing a suitable space for the feed hopper 33.

The bottom of this feed hopper is spaced a short distance from the inner surface of side 28 and from the inner surface of side 32 so as to form an L-shaped opening 34, through

which the material is fed onto the upper surface of the table. In the embodiment shown the table is covered by means of a sheet of copper which has been designated by reference numeral 35 and which has been provided with a plurality of parallel spaced riffles 36. The surface between these riffles is preferably flat and the riffles terminate a short distance from the inner side of end wall 30 so as to leave a flat

strip along this wall and this strip has been des-

gnated by reference numeral 37. A pipe 38 extends from the hopper 33 to the outer end of end wall 30, and this pipe is provided on its inner surface with openings through which water sprays 39 emerge. These sprays are directed against the inner surface of the walls and the water will flow in a uniform sheet over the surface of the table towards the open side thereof in the general direction of arrows 40. Water under pressure is supplied to the pipe 38 through a hose 41. The end wall 30 is provided near its outer end with an opening 42, which communicates with the interior of a box or receptacle which is formed by a bottom member 43, side member 44 and end walls 45. The copper plate 35 extends into this box or receptacle and forms the bottom of this box is provided with a longitudinal depression 46 which is adapted to contain mercury 47. Deflectors 48 are inserted through the opening and extend into the pathway of the moving concentrates and serve to direct them into the receptacle where they will be retained and where the metallic parts thereof will become amalgamated with the mercury. The table is adjusted so that the corner indicated by A is the highest point on the table, and that indicated by B is the lowest point. The table is usually adjusted so that it is upwardly inclined from the feed hopper towards the end 30 but it may be on a level in a longitudinal direction but must always be inclined from side wall 28 towards the open side.

For the purpose of reciprocating the table, I have provided a shaft 49 which is mounted for rotation in bearings 50. This shaft carries a cam 51, which is preferably made of rubber composition that has been clamped between metal plates 52. A belt wheel 53 is secured to one end of the shaft and power can be applied to this wheel by means of a belt which is connected with a motor or an internal combustion engine. Located on each side of the cam are guide members 54 that are provided with slots 55 through which the shaft extends. A roller 56 is mounted 45 for rotation between the guides 54 and contacts with the outer surface of the cam. Two connecting rods 57 extend from the guides 54 to the cross bar 58. This cross bar is supported on a threaded bar 59 whose ends are secured to the under side of the table by means of brackets 60. A bracket 61 is connected with the supporting frame and extends upwardly beyond the bar 59 and has an opening through which this bar projects. A spring 62 encircles the bar 59 and has 50 one end abutting the bracket 61. A nut 63, which is threadedly connected with the bar, serves as an abutment for the other end of the spring. A spring 64 is located on the side of the cross bar 58 which is nearest to the cam and one end of this spring is engaged by nut 65 threadedly connected with the bar. On the other side of this cross bar is another spring which has been indicated by numeral 66 and which extends between the cross bar and the nut 67. The springs 62 and 64 are quite strong while spring 66 is much lighter. The result of having spring 66 lighter will be explained hereinafter.

Let us now assume that the parts have been assembled in the manner shown and described 70 and that shaft 49 is rotated at a certain speed in the direction shown in Fig. 6. This cam has a portion thereof nearer to the center and therefore as it rotates the roller 56 will be moved away from shaft 49 and this will carry with it the 75 table. The force exerted by the rotating cam

will be transmitted to the table by the cross bar 58 and the spring 64, and will be resisted by spring 62, which abuts the bracket 61. The spring 66 exerts its force in opposition to spring 64 and the latter will, therefore, be compressed more than it otherwise would be by a given force applied by the connecting rods 57. When the cam has rotated to the position shown in Fig. 6, spring 62 will move the table towards the right and after a short time the table will start reciprocating at a rate corresponding to the speed at which the cam rotates. As the table with its load has a considerable amount of inertia, its amplitude of vibration will be greater than the eccentricity of the cam for the reason that the 10 springs by which it is connected to the frame and to the cross bar 58 will yield and permit the table to travel in either direction after the cross bar 58 has stopped moving, and in this manner the 15 effect of the cam will be multiplied to an appreciable extent.

Let us now assume that the table is in operation and that pulp is fed to the hopper 33. This pulp will pass through opening 34 onto the table and will pass along the table. The water that 25 is delivered to the table through pipe 38 will flow crosswise of the table and carry away the light portions of the pulp. The heavier parts of the pulp, such as the metallic values therein, will pass along the flat surfaces between the 30 riffles and will be subjected to an action similar to the panning action that takes place when an ordinary miner's pan is used. The greater portion of the values will flow between the side wall 28 and the riffles 36, and will pass along the flat 35 border 37 until it strikes the first deflector 48 and will then pass into the box 43. As water will continually circulate through this box the gangue that is carried thereinto will be removed by the action of this water. By having several 40 deflectors, it is possible to more accurately adjust the inflow and outflow and thereby secure a better cleaning action within the box 43 than could be obtained with a single deflector.

From the above description it will be apparent 45 that I have produced a concentrating device of a simple and substantial construction that can be readily transported to any place where it is to be used and which subjects the material to a panning action that very effectively separates 50 the valuable from the nonvaluable materials.

Although this device is intended primarily for use in connection with mineral ores it can also be employed for separating dry materials.

Owing to the fact that this machine has broad 55 flat surfaces between the riffles and that the reciprocation takes place in the direction of the riffles, I find that it is possible to separate gold of all sizes including the so-called flour gold, and that it is also possible to effect a separation of 60 dry materials although, for the best results, water should be employed in connection therewith.

Having described the invention what is claimed as new is:

1. In a device of the type having a supporting frame and a movable member located above the frame and mounted for rectilinear movement, means for reciprocating the movable member in the direction of its length, said means comprising a cam rotatably secured to the frame, a threaded rod located below the movable member and extending therealong in the direction of the length of the movable member, a bracket secured to the frame and projecting upwardly 70 therefrom, said bracket having an opening 75

- through which the rod extends, a spring (62) surrounding the rod on the side of the bracket farthest from the cam, one end of the spring abutting the bracket, a nut threadedly connected 5 with the rod and held in engagement with the other end of the spring, two spaced nuts secured to the rod on the side of the bracket nearest the cam; a cross bar slidably connected with the threaded rod between the two nuts, a spring 10 interposed between each side of the cross bar and each of the last named nuts, the spring between the cross bar and the bracket being weaker than either of the other two springs, a connecting rod secured to each end of the cross bar, said 15 connecting rods extending across the shaft to which the cam is secured and a roller mounted for rotation between the ends of the connecting rods, said rollers contacting with the cam whereby when the cam is rotated the movable member 20 will be reciprocated.
2. In a device of the type having a supporting frame, and a movable member located above the frame and supported for rectilinear movement, means for reciprocating the movable member in 25 the direction of its length, comprising a cam
- rotatably secured to the frame, a rod located underneath the movable member with its axis parallel to the direction in which the movable member moves, means for securing the ends of the rod to the movable member, a bracket secured to the frame and provided with an opening through which the rod extends, the rod having a threaded portion adjacent the bracket, a nut on the threaded portion, a compression spring located between the bracket and the nut for exerting a force tending to move the movable member in one direction, a connecting rod having one end provided with a roller which is positioned to engage the cam, means for guiding the end of the connecting rod that is adjacent the cam, 15 a cross head carried by the other end of the connecting rod, the cross head having an opening through which the threaded bar extends, a spring carried by the bar on opposite sides of the cross head and abutments for the ends of the spring 20 for holding them under compression whereby the movable member can move in either direction relative to the cross head.
